SUBMARINE MINE

Wilson R. Maltby, Washington, D. C.

Application July 30, 1941, Serial No. 404,608

20 Claims. (Cl. 102—13)

(Granted under the act of March 3, 1883, as
amended April 30, 1928; 370 O. G. 757)

This invention relates to a submarine mine of the induction or gradient type in which the mine is caused to be fired by the passage of a steel vessel or any vessel having a ponderance of magnetic material within an effective area adjacent the mine whereby the destructive effect of the mine upon the vessel will be assured. More specifically the invention provides a new and improved submarine mine adapted to be launched from an aircraft in flight in which means are provided for causing the mine to come to rest on the bed of a body of water with the mine in a vertical position.

In devices of this class heretofore devised, it is the general practice to allow the mine to come to rest in a random position determined only by such fortuitous circumstances as may be present incident to the launching of the mine. It is the usual practice in devices of this character to suspend the mine firing control unit on gimbals, whenever practicable, in order that the firing control mechanism may be placed in a predetermined position regardless of the position of rest that the mine has assumed. In the case of mines employing induction or gradiometer type coils for the control of the firing mechanism, the length of the coil employed precludes the effective use of gimbals for supporting the coil structure and such mines have been subject heretofore to the disadvantages which result from the placement of the axis of the search coils employed in varying degrees of tilt including a tilt to the horizontal position.

One of the objects of the present invention is the provision of new and improved means for directing a submarine mine along a predetermined path of flight when launched from an aircraft, for automatically decelerating the rate of travel of the submarine mine during passage of the mine through the body of water within which the mine has been launched, and for causing the mine to come to rest in an upright position on the bed of the body of water.

Another of the objects resides in the provision of new and improved means for rigidly supporting the mine in a predetermined position as the mine comes to rest on the bed of a body of water within which the mine has been launched.

Another of the objects is the provision of means effective as the mine strikes the bed of the body of water within which it has been launched for engaging the bed at different points whereby the mine is firmly braced in a vertical position regardless of the contour of the bed with which the mine is engaged.

Other objects and advantages will be apparent from the following detailed description, taken in connection with the accompanying drawings, of which:

- 5 Fig. 1 illustrates the invention according to a preferred embodiment thereof;
- Fig. 2 is a view in section, somewhat enlarged and partly broken away, of the device of Fig. 1;
- Fig. 3 is a view in elevation of the device of Fig. 2 with the fins thereof in open position;
- 10 Fig. 4 is a view partly in section and somewhat enlarged of the fin operating and latching mechanism;
- Fig. 5 is a view taken substantially along the line 5—5 of Fig. 4 with the fin in an extended position;
- 15 Fig. 6 is a view partly in section and partly broken away illustrating the fin releasing mechanism;
- Fig. 7 is an end view of the device of Fig. 6; and
- 20 Fig. 8 illustrates diagrammatically an electrical circuit arrangement suitable for use with the present invention.
- 25 Referring first to Fig. 1 of the drawings there is shown thereon a submarine mine indicated generally by the numeral 1 adapted to be released in any well known manner from an aircraft in flight such, for example, as illustrated
- 30 at 2, the path of travel of the mine being indicated generally by the dashed line 3. The mine is provided with a plurality of rotatable members or fins 4 pivotally mounted as at 5 but normally restrained from movement until released
- 35 by a hydrostat responsive to the pressure of the water within which the mine is launched whereby the members 4 are first employed as stabilizing planes or fins to guide the mine along a predetermined line of flight after being released from
- 40 the aircraft and are subsequently employed to decelerate the mine during the descent thereof through the water whereby the mine will strike the bed of the body of water at a somewhat reduced rate of travel. At the instant of impact
- 45 with the bed, the members are quickly brought into engagement with the bed thereby to maintain the mine securely braced in an upright position regardless of the contour of the bed of the body of water with which the mine is engaged.
- 50 The mine is provided preferably with a piercing member 6 adapted to penetrate the bed of the body of water and prevent substantial movement of the mine from any cause such, for example, as the action of tidal currents or a shifting condition of the bed. As illustrated on Fig. 1,

the mine is adapted to be braced in a vertical position on a relatively level bed of a body of water, on an inclined portion of the bed or upon a rock or reef such as illustrated at 7, 8, and 9, respectively.

On Figs. 2 and 3 is shown a submarine mine according to a preferred embodiment of the invention comprising a casing 11 to which is affixed the piercing member 6. The casing is provided with a tapered portion 12 having a cylindrical member 13 secured thereto as by the bolts 14, a suitable gasket 15 being provided preferably to insure a watertight connection between the casing and the tapered portion 12. Secured to the member 13 as by the bolts 16 is the member 17, a suitable gasket 18 being preferably inserted therebetween to prevent the seepage of water within the mine. The member 17 is provided with a bearing support or strap 19, Fig. 6, secured thereto in any suitable manner as by the bolts 21, and having a bearing 22 therein in alignment with the bearing 23 whereby the hydrostat plunger 24 is slidably supported. A flexible diaphragm 25 is secured in sealed relation to the plunger as by the nut 26 and to the member 17 as by the retaining ring 27 and bolts 28.

The plunger is provided with a latch 29 secured thereto and having four extending members 31 adapted to pass freely through suitable apertures within the member 17. A retractile spring 32 causes the hydrostat to remain in the extended position illustrated until the mine has attained a predetermined depth of submersion within the water, at which time the pressure of the water against the flexible diaphragm 25 causes the extending members 31 of the latch 29 to be withdrawn from locking engagement with the fin retaining hasps 33 pivotally secured to the fins as by the pins 34.

An arming wire 35 passes through an aperture 36 within the plunger rod 24 and the bearing supports 37 extending from the member 17 whereby the hydrostat is prevented from movement until after the arming wire is withdrawn. The arming wire extends through an aperture 38 within the member 17 and is secured at the other end thereof to the aircraft whereby the arming wire is withdrawn from the mine as the mine falls away from the aircraft.

Clamped to the mine casing 11 as by the bolt 39 is an adjustable support 40 comprising four bearing pieces 41 and a plurality of brackets 42 adapted to receive a bearing pin 43 held in position as by the cotter pins 44, Figs. 4 and 5. A rotatable member 45 having a ratchet device 46 secured thereto in any suitable manner such, for example, as by welding or brazing the parts together is pivotally mounted on the pin 43 whereby the member 45 may be rotated to different positions as will more clearly appear as the description proceeds. The member 45 is generally U shaped, Fig. 7, and provided with reinforcing strips secured thereto; such, for example, as the channel shaped pieces 47 illustrated.

A flexible cable 48, Fig. 4, of steel or similar material suitable for the purpose is secured at one end thereof to the ratchet 46 as by the plate 49 and bolts 51 and at the other end thereof to a retractile spring 52 as by the clamp 53 and bolt 54. The other end of the retractile spring is attached to a support 55 secured to the casing of the mine whereby the retractile spring is maintained in tension sufficient to cause the fin 45 to be actuated to the open position shown on Fig. 3. The cable 48 passes along a complementary

grooved arcuate portion 50 of the ratchet 46 and is guided by a suitable grooved pulley 56 pivoted on the bearing shaft 57 supported by the bearing pieces 41. A pair of pawls 58 and 59, Figs. 4 and 5, are pivotally supported on the shaft 57 and urged by the springs 61 and 62 respectively encircling the pin 63 toward the ratchet 46 until arrested by the portion 64 thereof whereby the pawls are prevented from engaging the arcuate portion 65 of the ratchet and are effective to engage any of the teeth 66 of the ratchet as the fin 45 is moved to an extended or open position. Pawl 59, it will be noted, is preferably somewhat longer than the pawl 58 by an amount substantially one-half the distance between the tips of adjacent teeth 66 of the ratchet, thereby providing an arrangement in which the angular distance between successive locking positions of the fin is one-half the angular distance between successive teeth of the ratchet. Thus, larger teeth on the ratchet may be employed in which the strength of the ratchet mechanism is substantially increased. This arrangement is clearly shown on Fig. 5 by reason of the fin 45 having been rotated, for purposes of illustration, through an angular distance of 90 degrees from the position shown on Fig. 4.

The support 55 is of a shape adapted to engage and additionally support the fin 45 during the flight of the mine in the air and the passage of the mine through the water until the hydrostat 25 has released the fins 45 which are moved by the springs 52 out of engagement with the supports 55. By pivotally supporting the fins at the pins 43 and additionally supporting the fins by means of the brackets 55 in the manner herein disclosed, the fins are rigidly held in a predetermined position in alignment with the axis of the mine whereby the mine follows a predetermined line of flight and may thus be planted in a predetermined location with a high degree of accuracy.

Attached to the adjustable support 40 in substantial alignment with the fins 45 are the V or wedge shaped members 67 whereby, during the descent of the mine within the water, after the fins have been released by the hydrostat, the members 67 deflect the pressure of the water from the fins sufficiently to permit the fins to be partially extended by the springs 52 in the manner shown on Fig. 1. The rate of descent of the mine is thus diminished until the mine strikes the bed of the body of water, at which time the inertia of the partially extended fins is employed to assist the springs 52 in quickly lowering the fins into engagement with the bed of the body of water before the mine has tilted by an appreciable amount from the vertical position. Each of the fins is restrained from reverse movement by the pawl 58 or 59, as the case may be, whereby the mine is positively set to a predetermined vertical position. The adjustable support 40 may, if desired, be clamped at different positions with respect to the mine casing 11 whereby the position of the fins 45 may be varied at will in accordance with the degree of hardness of the bed of the body of water within which the mine is to be planted. A plurality of holes 69 are provided in each of the fins 45 whereby the hasp 33 may be pivotally secured thereto by the pin 34 at different positions in accordance with the adjusted position of the support 40. If for example, the mine is to be launched in a body of water having a relatively soft bed, it may be desirable, in view of the greater penetration of the mine within the bed before coming to rest, to arrange the support 40 somewhat nearer the tail of the mine whereby the fins 45 may be

employed to greater advantage in supporting and maintaining the mine in a vertical position.

The operation of the mine firing mechanism will now be described. Assume, by way of example, that the mine has been launched and is resting on the bed of a body of water in a vertical position with the fins thereof locked in supporting engagement with the bed and that sufficient time has elapsed after the mine has been launched for the soluble washer 68 to dissolve or soften sufficiently to allow the hydrostat 69 to be operated by the pressure of the water. When this occurs, the detonator 71 is inserted into the booster charge 72 within the casing 73 and the electrical contact members 74 are brought into engagement with each other by movement of the collar 75 preferably of insulating material suitable for the purpose such, for example, as Bakelite, rubber or the like, affixed to the hydrostat.

A battery BA is provided within the compartment 76, Fig. 6, and insulated therefrom by suitable yieldable material such, for example, as sponge rubber or the like in the manner illustrated and in circuit with the armature spring 77 of relay F, the circuit being continued by way of the cable duct 78 to the hydrostat contacts 74 and thence to the detonator 71. A search coil SC preferably having a magnetic core 80 therein is operatively connected to the winding of relay F as by the conductors 79 and adapted to operate the relay in response to a changing field detected by the search coil within the effective destructive area above the mine. Thus, the electromotive force generated by the search coil, as a steel vessel passes within the effective area of the mine, is of sufficient strength to operate the relay F and cause the detonator 71 to operate and fire the booster charge 72 thereby causing the main charge 79 to explode the mine.

Whereas the preferred illustrative embodiment of the invention has been described with particular reference to a submarine mine in which an induction coil is employed to control the mine firing mechanism, it will be understood that the present invention may be applied to mines in which the presence of a steel vessel is detected by search coils of the gradient type wherein the differential voltages induced within the search coils by the moving vessel is employed to fire the mine. The invention may also be employed with mines in which the detecting mechanism is preferably directionally disposed such, for example, as mines employing acoustically controlled detecting mechanisms.

Briefly stated in summary, the present invention provides means for guiding a submarine mine both through the air and in the water along a predetermined line of flight and causing the mine to come to rest and be braced in a vertical position on the bed of the body of water within which the mine has been launched. Thus, by reason of the predetermined position of rest of the mine, the area detected by the detecting mechanism is reduced and a more effective use is made of the mine for the purpose of disabling or destroying a vessel.

While there is shown and described herein a certain preferred embodiment of the invention, many other and varied forms and uses will present themselves to those versed in the art without departing from the invention, and the invention, therefore, is not limited either in structure or in use except as indicated by the terms and scope of the appended claims.

The invention herein described and claimed may be manufactured and used by or for the Government of the United States of America for governmental purposes without the payment of any royalties thereon or therefor.

What is claimed as new and desired to be secured by Letters Patent of the United States is:

1. In a mine of the character disclosed adapted to be laid on the bed of a body of water, a mine casing having a plurality of fins pivotally secured thereto and settable to an initial position and to a final position in which the fins are adapted to support the mine in a predetermined position on said bed, means for locking said fins in said initial position, means effective during the descent of the mine through the water for causing the fins to be released from said locking means, and means for actuating the fins to said final position as the mine strikes the bed of the body of water within which the mine has been launched.

2. In a mine of the character disclosed adapted to be laid on the bed of a body of water, a mine casing having a plurality of fins pivotally secured thereto and settable to an initial position and to a final position in which the fins are adapted to support the mine in a predetermined position on said bed, means for locking said fins in said initial position, means effective during the descent of the mine through the water for causing the fins to be released from said locking means, means for actuating the fins to said final position as the mine strikes the bed of the body of water within which the mine has been launched, and means for retaining the fins in said final position.

3. In a mine of the character disclosed adapted to be laid on the bed of a body of water, a plurality of rigid members pivotally secured to said mine adapted to brace the mine in an upright position as the mine comes to rest on said bed, means for maintaining the members in a closed position as the mine is launched, means including a device responsive to the pressure of the water within which the mine is immersed for releasing said rigid members, and means effective as the members are released for actuating the members to an open bracing position.

4. In a mine of the character disclosed adapted to be laid on the bed of a body of water, a plurality of rigid members pivotally secured to said mine adapted to brace the mine in an upright position as the mine engages said bed, means for maintaining the members in a closed position as the mine is launched, means including a device responsive to the pressure of the water within which the mine is immersed for releasing said rigid members, means effective as the members are released for actuating the members to an open bracing position, and means including a ratchet mechanism for locking said rigid members in said open bracing position.

5. In a submarine mine adapted to be launched from an aircraft in flight, the combination of a plurality of fins pivotally secured to said mine, fin actuating means for pivotally moving the fins from a predetermined initial position to a final position in which the fins are adapted to support the mine in a predetermined launched position, means for retaining said fins in said predetermined initial position, an arming wire secured to said aircraft and adapted to unlock said fin retaining means as the mine falls away from the aircraft in flight, and means for rendering said fin retaining means ineffective to maintain the fins in said predetermined initial position during

the travel of the mine through the body of water within which the mine is launched.

6. In a submarine mine adapted to be launched from an aircraft in flight, the combination of a plurality of fins pivotally secured to said mine, fin actuating means for pivotally moving the fins from a predetermined initial position to a final position in which the fins are adapted to support the mine in a predetermined launched position, means for retaining said fins in said predetermined initial position, an arming wire secured to said aircraft and adapted to unlock said fin retaining means as the mine falls away from the aircraft in flight, means for rendering said fin retaining means ineffective to maintain the fins in said predetermined initial position during the travel of the mine through the body of water within which the mine has been launched, and means secured to said mine for causing the fins to be actuated to a predetermined setting during the descent of the mine through said body of water.

7. In a mine of the character disclosed adapted to be launched from an aircraft in flight, the combination of a plurality of rigid members pivotally and releasably secured to said mine for directing the mine along a predetermined line of flight, means effective during the descent of the mine through the water for releasing said rigid members, and means effective as the mine strikes the bed of the body of water for causing said rigid members to be actuated into engagement with said bed variably in accordance with the contour of said bed thereby to support the mine in a vertical position.

8. In a mine of the character disclosed adapted to be launched from an aircraft in flight, the combination of a plurality of rigid members pivotally and releasably secured to said mine for directing the mine along a predetermined line of flight, means effective during the descent of the mine through the water for releasing said rigid members, means effective as the mine strikes the bed of the body of water for causing said rigid members to be actuated variably to positions in engagement with said bed in accordance with the contour of the bed thereby to support said mine in a vertical position, and means for locking said members in said actuated positions.

9. In a submarine mine adapted to be launched from an aircraft in flight, means effective as the mine comes to rest on the bed of a body of water within which the mine has been launched for engaging said bed and supporting the mine in a predetermined position, means for locking said mine supporting means in an initial position, an arming wire secured to said aircraft for removing a restraint said locking means as the mine falls away from said aircraft, means controlled by the pressure of the water for releasing said locking means, means for actuating said mine supporting means to a position in which the rate of travel of the mine through the water is reduced and for additionally actuating the mine supporting means as the mine strikes said bed, and means for latching said bracing means in engagement with the bed of the body of water in accordance with the contour of said bed.

10. In a mine of the character disclosed adapted to be launched from an aircraft in flight, the combination of a plurality of fins pivotally secured to said mine, means for actuating said fins to different positions, a ratchet member secured to each of said fins having a plurality of ratchet teeth thereon, a pair of pawls adapted to engage

the teeth of each ratchet member alternately as the fin is actuated to successive positions for locking each of said fins in different positions in accordance with the contour of the bed of the body of water with which the fins are engaged.

11. In a mine of the character disclosed adapted to be launched from an aircraft in flight, the combination of a plurality of fins pivotally secured to said mine, means for actuating said fins to different positions, a ratchet member secured to each of said fins having a plurality of ratchet teeth thereon, a pair of pawls adapted to engage the teeth of each ratchet member alternately as the fin is actuated to successive positions for locking each of said fins in different positions in accordance with the contour of the bed of the body of water with which the fins are engaged, and means for urging said pawls against said ratchet member.

12. In a submarine mine adapted to be launched from an aircraft in flight, a plurality of fin members for controlling the flight of said mine through the air, a plurality of pivot supports for said fins, means for moving said fins into engagement with the bed of the body of water within which the mine has been planted thereby to support the mine in a predetermined position, and means for adjusting the position of said pivot supports in accordance with the predetermined degree of penetration of said bed by the mine.

13. In a submarine mine adapted to be released from an aircraft in flight, a plurality of fin members for controlling the flight of the released mine, means for pivotally supporting said fin members, means for locking said members in an initial position, means controlled by the pressure of the water within which the mine is submerged for simultaneously releasing each of the fin members from said locking means, and means adapted to actuate said fin members to an outwardly extending open position in which the fin members are adapted to decelerate the descent of the mine within the water as the members are released by said releasing means.

14. In a submarine mine adapted to be launched from an aircraft in flight, the combination of a mine comprising a casing having a plurality of movable members pivotally secured thereto and settable to an initial guiding position and to a final bracing position, means for holding the members in said initial position, a ratchet individual to each of said members and secured thereto, a plurality of pawls adapted to engage the teeth of each ratchet respectively and to retain the members in said bracing position, means for releasing said holding means during the descent of the mine within the body of water, and means including a flexible member in operative connection with each of said ratchets respectively for actuating said members to said final position after said holding means has been released.

15. A submarine mine of the character disclosed adapted to be released from an aircraft in flight and having a plurality of movable fins for guiding the mine along a predetermined line of flight, a mine casing, means connected to the casing for pivotally supporting said fins, means for preventing movement of the fins from an initial position until the mine has been submerged to a predetermined depth within a body of water, means including a spring device for actuating each of said fins to an outwardly extending open position in which the fins are adapted to decelerate the descent of the mine

within the water, means secured to said casing and adapted to be enclosed by the fins while in said initial position for additionally supporting the fins, and means for connecting said spring device to the last named fin supporting means.

16. In a submarine mine of the character disclosed comprising a plurality of rotatable fins adapted to be actuated to a position in which the fins are adapted to support the mine in a predetermined launched position, the combination of ratchet mechanism rotatable with each of said fins, means for actuating said fins, a plurality of pawl devices for engaging the teeth of said ratchet mechanism variably in accordance with the angular position of said fins, a pivot support for said pawl devices, means adapted to urge the pawls into engagement with said ratchet mechanism, and means for preventing the engagement of said ratchet mechanism by said pawls until the fins have been rotated by said actuating means through a predetermined degree of rotation.

17. In a submarine mine of the character disclosed, the combination of a mine casing having a plurality of fin members pivotally secured thereto and locked in an initial position, means including a device responsive to the pressure of the body of water within which the mine has been launched for releasing said fin members for rotation, means for actuating said fin members to a final setting in which the mine is braced in a predetermined position as the mine comes of rest on the bed of said body of water, a water hydrostat having contact means adapted to be closed as the hydrostat operates in response to a predetermined degree of pressure of the water within which the mine is submerged, means including a relay for detecting the presence of a vessel within an effective destructive area, detonating means, and means including a firing circuit adapted to be closed jointly by said contact means and said relay for causing the detonating means to explode the mine in response to the operation of said sensing mechanism.

18. A submarine mine of the character disclosed adapted to be laid on the bed of a body of water, a casing for said mine having a plurality of bracing members pivotally secured thereto and settable to an initial position and to a final position in which said bracing members are

adapted to brace the mine in a predetermined position on said bed, means for releasably locking said bracing members in said initial position, a hydrostat device having means for causing the

5 bracing members to be released from said locking means as the hydrostat device operates, means adapted to actuate the bracing members to said final position, a plurality of stop members secured to said casing within the path of travel 10 of said bracing members for arresting the bracing members in said final position, and a plurality of ratchet devices respectively associated with each of said bracing members for locking the bracing members in said final position.

15. 19. A submarine mine of the character disclosed adapted to be launched within a body of water from an aircraft in flight, a plurality of fins pivotally secured to said mine, normally locked means for releasably retaining said fins

20 in a predetermined initial position, an arming wire secured to the aircraft and adapted to unlock said fin retaining means as the mine falls away from the aircraft, means responsive to the pressure of the water within which the mine is 25 launched for rendering said fin retaining means ineffective to maintain the fins in said predetermined initial position, and means secured to said mine for causing the fins to be actuated variably to different positions in which the fins 30 are adapted to support the mine in a predetermined position on the bed of said body of water in accordance with the rate of travel of the mine through said body of water.

20. In a mine of the character disclosed adapted 35 to be launched from an aircraft in flight, the combination of a plurality of rigid members pivotally secured to said mine for directing the mine along a predetermined line of flight, means for releasably locking said rigid members in an initial 40 position, means effective during the descent of the mine through the water for causing the rigid members to be released from said locking means, and means for yieldably urging said rigid members outwardly from the mine to different angular positions in accordance with the rate of 45 travel of the mine through the water thereby to vary the effective braking area of the members until a uniform rate of travel of the mine is reached.

WILSON R. MALTBY.
